CLAIM

The ornamental design for a firewall mount high AMP circuit breaker, as shown and described.

DESCRIPTION

FIG. 1 is a top, front and right side perspective view of a firewall mount high AMP circuit breaker showing our new design with the manual reset lever in its tripped position;

FIG. 2 is a top plan view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a bottom plan view thereof;

FIG. 8 is a top, front and right side perspective view of a firewall mount high AMP circuit breaker showing a second embodiment of our new design having an auto-reset;

FIG. 9 is a top plan view thereof;

FIG. 10 is a right side elevational view thereof;

FIG. 11 is a left side elevational view thereof;

FIG. 12 is a front elevational view thereof;

FIG. 13 is a rear elevational view thereof;

FIG. 14 is a bottom plan view thereof.
